DESIGN FOR A BARREL OR SIMILAR ARTICLE

John E. Garlent, Lansing, Mich., assignor to Motor Wheel Corporation, Lansing, Mich., a corporation of Michigan

Application July 14, 1933, Serial No. 48,712

Term of patent 14 years

To all whom it may concern:

Be it known that I, JOHN E. GARLENT, a citizen of the United States, residing at Lansing, in the county of Ingham and State of Michigan, have invented a new, original, and ornamental Design for a Barrel or Similar Article, of which the following is a specification, reference being had to the accompanying drawing forming a part thereof.

In the drawing:

Figure I is a side elevation of a barrel or similar article showing my new design; and

I claim:

The ornamental design for a barrel or similar article as shown.

In testimony whereof he has affixed his signature.

JOHN E. GARLENT.
